UNITED STATES PATENT OFFICE.

ALDUS FISHER, OF MALVERN, PENNSYLVANIA.

SAFETY DEVICE FOR TRACK SWITCHES AND SIGNALS.

Application filed December 9, 1921. Serial No. 521,149.

To all whom it may concern:

Be it known that I, ALDUS FISHER, a citizen of the United States, residing at Malvern, in the county of Chester and State of Pennsylvania, have invented certain new and useful Improvements in Safety Devices for Track Switches and Signals, of which the following is a specification.

One object of my invention is to provide an improved device of simple construction which can be readily connected mechanically and electrically with the switch operating and signal controlling mechanism of railroads; the arrangement and construction of the parts being such that they will not interfere with the free access to other necessary connected and associated parts such for example as the usual longitudinal locking bars.

Another object is to so construct my improved device that its capacity for signal control can be readily increased.

These objects, and other advantageous ends which will be described hereinafter, I attain in the following manner, reference being had to the accompanying drawings in which

Figure 1 is a diagrammatic view showing the arrangement of my improved device connected to switch throwing mechanism and illustrating one embodiment of my invention.

Figure 2 is a face view of a device constructed in accordance with my invention capable of being connected as illustrated in Figure 1.

Figure 3 is a side view of Figure 2.

Figure 4 is a section taken on the line 4-4 of Figure 2.

Figure 5 is an enlarged section taken on the line 5-5 of Figure 2.

Figure 6 is an enlarged section taken on the line 6-6 of Figure 2.

Figure 7 is a view of the same general character as shown in Figure 2 and illustrating certain of the parts having been moved into another position.

Figure 8 is a view of the same general character as shown in Figures 2 and 7 illustrating the parts moved into another position.

Figure 9 is a section taken on the line 9-9 of Figure 2.

Figure 10 is a section taken on the line 10-10 of Figure 7.

Figure 11 is a section taken on the line 11-11 of Figure 8.

Figure 12 is a side elevation of a locking bolt which I preferably employ.

Figure 13 is a top plan view of said bolt.

Figure 14 is a view of the opposite side of said bolt, and

Figure 15 is a fragmentary perspective view of a cam plate which forms a part of my invention.

Referring to the drawings, 16 represents a supporting structure which may be made of cast metal or of plate metal; the same including bearings 17 for a rock shaft or bar 18; said rock shaft having thereon a drum or cylinder 19 of electrical non-conducting material. This cylinder 19, at positions spaced apart within its length, has segments 20, 21, 22, 23, 24 and 25 of electrical conducting material on its outer face. The number of these segments can be readily varied or if desired any number of cylinders similar to 19 can be secured to the rock shaft without in any manner effecting the upper parts hereinafter described.

A block 26 of electrical non-conducting material such for example as porcelain is secured between the cylinder and the supporting structure 16 and said block has binding posts 27 on either side to which electric conduit wires can be attached and said binding posts also serve to secure sets of electric contacting shoes 28 adjacent opposite sides of the cylinder so as to engage the various segments at certain times so that the segments under certain conditions are capable of completing an electric circuit between opposed shoes of each set. It will be noted, however, that by rotating the cylinder the segments can be moved into positions to break the various segments and in the use of the device the segments are placed in various positions one relative to the other so that while certain of the segments are completing electric circuits between their respective shoes others of the segments will serve to break or open the circuits between their respective shoes.

The supporting structure 16 has forwardly projecting strips 29 providing a slideway 30 for a reciprocating member 31 in the form of an elongated plate. This plate adjacent its lower end has cams 32 and 33 which have forward surfaces which slant in opposite di-

rections with respect to the forward face of the plate 31; said cam faces also being beveled one outwardly and the other inwardly. The rock shaft 18 has a T-shape head 34; 5 one extension 35 being adapted to engage the cam 32 and the other extension 36 being adapted to engage the cam 33 so that a reciprocating movement of the plate 31 will impart a rocking or oscillating movement to 10 the rod 18 and consequently to the cylinder 19. The plate 31 has an angularly disposed rib cam 37 adapted to fit within a slanting groove 38 in a bolt 39; said bolt being slideable in a slideway 40 which extends transversely of the slideway 30. This bolt in its forward surface has a central recess 41 separated from two end recesses 42 and 43 by projections 44 and 45. Two electromagnets 46 are secured to the supporting structure 15 and have an armature 47 which is pivoted at 48^a; said armature having a depending arm 48 which serves as a latch for co-operative engagement with the bolt 39 in a manner hereinafter described. The means providing 20 the slideway 40 is cut away between its ends to provide an entrance opening 49 for the latch 48 to engage the bolt 39 when the electro-magnets 46 are de-energized. However, it will be noted that when the electro- 25 magnets are electrically energized their cores will attract the armature and cause the latch 48 to be moved outward into the dot-and-dash line position shown in Figure 4 so as to release the bolt 39. When the bolt 30 is thus released the cam plate 31 can be moved upward or downward and said movement of the cam plate will effect a sliding movement of the bolt within its slideway in a direction depending upon the direction of 35 movement upward or downward of the cam plate 31. However, when the latch 48 is within any of the recesses above mentioned the movement of the cam plate 31 will be arrested due to the engagement of either one 40 of the projections 44 or 45 with the latch with the exception that when the latch is within the recess 41 a slight movement of the bolt is possible since said recess is of greater width than the width of the latch. 45

50 In Figure 1, I have shown my improved device operatively connected by attaching a link 50 to the upper end of the cam plate 31 and to the slotted link or segment 51 which is usually employed in connection with the switch-operating lever; said slotted segment being pivotally mounted at 52 within its length. An operating lever 53 is pivotally mounted at 54 below the floor level 55 of an operating tower and this operating lever 55 carries a pivoted hand grasp lever 56. The hand grasp lever may be of the usual construction and has a rod 57 pivotally connected thereto; said rod at its lower end having a block 58 slideable in the slot 59 of the segment 51. The usual quadrant base 60

is provided adjacent the segment 51 and at its opposite ends has shoulders 61 and 62 so that an extension of the block 58 can be moved into engagement with said shoulders when the operating lever is in its forward and rear swinging positions. 70

A spring 63 normally tends to move the block 58 downward and to keep the hand grasp lever 56 in a position remote from the upper end of the operating lever; it also being noted that this spring 63 serves to keep the segment 51 swung in one position or the other according to the position of the operating lever and therefore if the hand grasp lever 56 is moved on its pivot toward the upper end of the operating lever the block 58 will be raised from the position shown in Figure 1 and the segment 51 will be rocked on its pivot 52. If, after said movement of the block and segment 51, the operating lever 53 is swung on its pivot 54 to its extreme rear position and then the hand grasp lever 56 is released, the block 58 will continue to swing said segment by pushing the opposite end thereof downward until the extension of the block finds its place to the rear of the shoulder 62. In so far as the operating levers, the segment 51 and the quadrant base 60 is concerned they may be of any of the usual construction and the lower end of the operating lever 53 is illustrated as connected to the switch portion 63 of a side track 64 and main track 65 as shown in Figure 1. It will be noted however that when the hand grasp lever 56 is moved toward the upper end of the operating lever 53 that the link 50 will be raised a certain distance and that when the lever 53 is swung until the block 58 passes the pivot 52 and the hand grasp lever 56 is released the segment 51 will be rocked to a greater extent and the link 50 will be raised to a greater extent. In other words, the mere movement of the hand grasp lever toward the upper end of the operating lever 53 moves the cam plate 31 one-half of its possible upward movement and when the hand grasp lever 56 is released, after the movement of the operating lever past the pivot 52, the cam plate will be raised the other half of its possible upward movement. 100

I have illustrated the switch connecting rod 66 attached to a swinging arm 67; said swinging arm having an electric contact member 68 thereon adapted to be moved into engagement with either of two contacts 69 and 70. The contact member 68 is in electric connection with an electric battery or generator 71 and this battery in turn is connected to one pole of the electro-magnets 46. The other pole of the electro-magnets is connected through the medium of a relay 72 and floor push switch 73 with two of the contact shoes 28 on one side of the cylinder 19; the opposed shoes being con- 105

110

115

120

125

130

ected one with the contact 69 and one with the contact 70. The coil 74 of the relay is shown in electric circuit with the opposed rails of the tracks 64 and 65; said rails also being in electric circuit with a battery or generator 75 at a distance spaced from the connection of the relay coil so that if any train, car or the like is on either of the tracks between the battery connection and the relay coil connection that the battery 75 will be short-circuited and the coil 74 de-energized. The relay includes an armature 76 which when the coil 74 is energized is held in bridging or circuit-closing connection with two contacts 77 and 78 which are interposed in the connection between the push switch 73 and the electro-magnets. A spring 79 is preferably connected to the armature 76 so that when the relay coil 74 is de-energized, the armature will be moved out of bridging connection with the contacts 77 and 78 so that no circuit can be completed therebetween even though the push switch 73 is actuated. The contact shoes 28 other than those connected to the contacts 69 and 70 can be electrically connected with signal devices in the usual manner.

In Figure 1 the track 65 is shown clear with the contact member 68 in engagement with the contact 69 and the segment 20 is in contact with both of its shoes 28; the push switch 73 being open so that the latch 48 is in the position shown in Figures 2 and 9 within the recess 43 against the extension 45 of the bolt; the cam plate 31 being illustrated in its lowermost position.

To throw the switch 63 to connect the track 64 with the main track 65 the operation is as follows: The push switch 73 is depressed and an electric circuit is completed through the electro-magnets and the armature is attracted and the latch is withdrawn from the recess 43 of the bolt 39. The hand grasp lever 56 is then swung toward the upper end of the operating lever 53 and this action effects the raising of the block 58 and the consequent swinging of the segment 51 to lift the cam plate 31 through the medium of the link 50. Since the bolt 39 is free to move, the rib cam 37 will move said bolt and thereby permit the cam plate 31 to continue in its upward movement. The operating lever 53 can then be swung to operate the switch and if there are no obstructions against the movement of the switch, the switch will be moved to its full limit and the contact member 68 will be moved into engagement with the contact 70 and upon release of the hand grasp lever 56 the spring 63 will operate to move the block 58 downward and impart an additional rocking movement to the segment 51 in the same direction and thereby continue to lift the cam plate 31 to its full upward position. This latter action will move, for

example, the segments 24 and 25 of the cylinder into circuit-closing connection with their respective shoes 28 and electric current is thereby supplied for operating the signals.

If, for any reason, the switch cannot be moved to its full extent the contact member 68 will not engage the contact 70 and the circuit will remain open and the electro-magnet will not be energized. The recess 41 in the bolt 39 is so positioned if such condition occurs that the latch 48 will be positioned therein and thereby lock the bolt and prevent the hand grasp lever from moving outward to its full extent away from the operating lever 53 and the operator will know that proper movement of the switch has not been effected. Furthermore owing to this action the segments 24 and 25 will not be moved to close the signal circuits through their respective shoes 28 and the signals which determine when the track 64 is in proper switching connection with the track 65, cannot be operated.

In the movement of the bolt 39 from the position shown in Figure 2 to the position shown in Figure 8, it will be noted that during this action the electro-magnets are de-energized to allow the latch to engage within the recess 41 and if all of the parts continue to be moved such for example as the throwing of a switch, the electro-magnets will be again energized to withdraw the latch due to the contacting of the segment 23 with both of its shoes 28.

Thus in the initial or starting position as shown in Figure 2 the circuit will be completed when the push switch 73 is operated owing to the fact that the segment 20 is in contact with both of its shoes 28. The initial upward movement of the cam plate 31 causes first the movement of the bolt and then all of the segments 20, 21, 22, 23, 24 and 25 move out of circuit-closing contact with their respective shoes. Then as shown in Figure 7 the contacting segment 23 moves into engagement with both of its shoes if the switch has been properly shifted and finally the contacting segments 24 and 25 come in contact with their respective shoes 28. It will be noted further that in the initial or starting position the contacts 21 and 22 are in circuit-closing connection with their respective shoes 28 so that the signal circuits are completed.

For the reverse movement of the operating lever 23, the parts operate similarly only in a reverse direction as obvious from the construction as illustrated. By arranging the parts as above described, the controlling means can be kept at a position away from the operating lever and its various connected and associated parts. In fact the device can be positioned adjacent a lower floor where access can be had to the device.

without removing or in any way being obstructed by the parts adjacent the operating means.

Furthermore, as previously stated, the capacity of the electric connecting means can be increased without altering, changing or re-constructing in any manner the operative parts for moving the cylinder or the means for controlling the locking of the bolt and cam plate. While the parts are all operatively connected they do not in any way interfere with access one to the other. Even for this reason alone my improved device is valuable for use in connection with switch and signal operating towers where the parts are usually congested near the controlling means.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

30 1. A device of the character described including signal controlling circuits; a support; a cylindrical circuit controller rockably mounted on the support; and means movable on the support in the direction of the length of the circuit controller for actuating it to make and break the circuits, substantially as described.

40 2. A device of the character described including signal controlling circuits; a support; opposed electrical contacts carried by the support; a shaft rockably mounted on the support; a non-conducting member on the shaft; conducting members thereon co-acting with the contacts, and means movable in the direction of the length of the shaft for actuating it to make and break the circuits, substantially as described.

50 3. A device of the character described including signal controlling circuits; a support; opposed electrical contacts in said circuits carried by the support; a rock shaft; a non-conducting member on the shaft; conducting members thereon co-acting with said circuits, and means movable in the direction of the length of the shaft for rocking it to make and break the circuits, substantially as described.

60 4. A device of the character described including signal controlling circuits; a support; a circuit controller controlling said circuits; a reciprocating member movable on the support in the direction of the length of the circuit controller; a bolt slideable on the support for locking the reciprocating member; means carried by the reciprocating

member for actuating the controller; means carried by the reciprocating member for slidably engaging and actuating the bolt, and means for automatically locking the bolt in selected positions, substantially as described.

5. A device of the character described including signal controlling circuits; a support; opposed electrical contacts in said circuits carried by the support; a rock shaft; a non-conducting member on the shaft; conducting members thereon co-acting with said contacts; a bolt slideable on the support; a reciprocating member movable on the support in the direction of the length of the rock shaft; means carried by the reciprocating member for actuating the rock shaft and the bolt, and means for automatically locking the bolt in selected positions, substantially as described.

6. A device of the character described including signal controlling circuits; a circuit controller; a reciprocating member for actuating the circuit controller; a slideable bolt; means on the reciprocating member for slidably engaging and actuating the bolt, and means for locking the bolt in selected positions, substantially as described.

7. A device of the character described including signal controlling circuits; a circuit controller; a reciprocating member for actuating the circuit controller; a slideable bolt; means on the reciprocating member for slidably engaging and actuating the bolt; means for locking the bolt in selected positions, the latter means including electro-magnets, an armature and a latch carried by the armature for locking engagement with the bolt, substantially as described.

8. A device of the character described including signal controlling circuits; a circuit controller; a reciprocating member for actuating the circuit controller; a slideable bolt; a cam on the reciprocating member adapted to slide the bolt and automatically operative means for locking engagement with the bolt, substantially as described.

9. A device of the character described including signal controlling circuits; a circuit controller; a reciprocating member for actuating the circuit controller; a slideable bolt having recesses; a cam on the reciprocating member for sliding the bolt; and a latch automatically movable into and out of the recesses, substantially as described.

10. A device of the character described including signal controlling circuits; a circuit controller; a reciprocating member for actuating the circuit controller; a slideable bolt having recesses; means for sliding the bolt; electro-magnets having a pivoted armature, and a latch fixed to the armature adapted to enter the recesses when the magnets are deenergized and to be with-

drawn when the magnets are energized, substantially as described.

11. A device of the character described including signal controlling circuits; a support; a rock shaft having a T-shaped head; a circuit controller carried by the rock shaft; a reciprocating member, and cams on the reciprocating member adapted to engage with the T-shaped head and alternately rock the shaft in reverse directions. 35

12. A device of the character described including signal controlling circuits; a support; a rock shaft having a T-shaped head; a circuit controller carried by the rock shaft; a reciprocating member; a bolt slidable transversely of the reciprocating member; cams on the reciprocating member adapted to actuate the rock shaft and the bolt, and means for locking the bolt in selected positions, substantially as described. 40

13. A device of the character described including rotatable means operative to effect the establishment of signal controlling circuits; reciprocating means operative to effect the rotation of said first means; a slidable bolt; means on said reciprocating means for sliding said bolt; and means for locking said bolt in various positions; substantially as described. 45

14. A device of the character described including rotatable means operative to effect the establishment of signal controlling circuits; reciprocating means operative to effect the rotation of said first means; a slidable

bolt; means on said reciprocating means for sliding said bolt; and means for effecting the locking of said bolt, said latter means including electro-magnetic means, an armature, and a latch operatively connected to said armature for locking engagement with said bolt; substantially as described. 50

15. A device of the character described including rotatable means operative to effect the establishment of signal controlling circuits; reciprocating means operative to effect the rotation of said first means; a slidable bolt; a cam on said reciprocating means for sliding said bolt; and means automatically operative for locking engagement with said bolt; substantially as described. 55

16. A device of the character described including rotatable means operative to effect the establishment of signal controlling circuits; reciprocating means operative to effect the rotation of said first means; a slidable bolt having recesses; a cam on said reciprocating means for sliding said bolt; and means automatically operative and including a latch movable into and out of said recesses; substantially as described. 60

In testimony whereof I have signed my name to this specification in the presence of two subscribing witnesses.
